UNITED STATES PATENT OFFICE.

LOUIS N. LEVINSOHN, OF NEW YORK, N. Y.

DESIGN FOR A CABINET.

41,391.

Specification for Design.

Patented May 16, 1911.

Application filed December 12, 1910. Serial No. 597,002. Term of patent 7 years.

To all whom it may concern:

Be it known that I, LOUIS N. LEVINSOHN, a citizen of the United States, residing in the city of New York, Richmond Hill, borough of Queens, county of Queens, and State of New York, have invented a new, original, and ornamental Design for a Cabinet, of which the following is a specification, reference being had to the accompanying drawing, forming part thereof.

The figure is a perspective view of a cabinet showing my design.

I claim:

The ornamental design for a cabinet as shown.

LOUIS N. LEVINSOHN.

Witnesses:

THEO. G. HOSTER,
PHILIP D. ROLLHAUS.
